Primary Examiner—Susan J. Lucas

Attorney, Agent, or Firm—Charles C. Logan, II

[57] CLAIM

The ornamental design for a candle, as shown and described.

DESCRIPTION

FIG. 1 is a front elevation view of candle showing my new design and this identical view occurs every ninety degrees around its perimeter;

FIG. 2 is an elevational view taken after rotating FIG. 1 through an angle of 45 degrees and this identical view occurs every ninety degrees around the perimeter of the candle;

FIG. 3 is a top plan view thereof; and,

FIG. 4 is a bottom plan view thereof.
